MULTIPLE IRONING MACHINE

John H. Leef, Minneapolis, Minn.

Application July 9, 1951, Serial No. 235,748

6 Claims. (Cl. 38—5)

1

My present invention relates to garment ironers and, more specifically, to improvements in multiple garment ironing machines utilizing a rotary supporting structure, whereby a number of ironers mounted on said supporting structure may be loaded and unloaded by a single operator positioned at an operator's station adjacent the track on which the supporting structure rotates.

More particularly, the present invention is in the nature of an improvement on the structure disclosed in my prior United States Letters Patent No. 2,556,477 and entitled "Multiple Ironing Machine."

Several machines of the above type utilize relatively stationary actuators to cause the pressing shoes of the several ironers to move from ironer open to ironer closed positions and vice-versa as the supporting structure rotates. These actuators usually are subject to an appreciable load when in operation and, for this reason, must be firmly anchored against movement in the direction of travel of the supporting structure. Heretofore, the practice has been to bolt or screw the actuators to the floor or base of support for the track on which the supporting structure rotates. If an error is made in the installation of the actuators, or if it is desired to shift the operator's station about the track, the entire machine, including the supporting structure, must be removed and new anchoring bolts drilled into the floor to receive the anchoring bolts. When the floor or base is of concrete or the like, this becomes a laborious task unless special drilling equipment is available. The primary object of my invention is, therefore, the provision of novel means for releasably anchoring the actuators in desired set positions in the path of circumferential travel of the actuator-engageable portions of ironer shoe-operating mechanism carried by the supporting structure, whereby said actuators may be adjustably moved longitudinally of the path of travel of the supporting structure when adjustment is required.

Another object of my invention is the provision of means for anchoring said actuators to the track upon which the supporting structure is mounted and which will eliminate the drilling of holes in the floor or other supporting surface for the actuators.

Another object of my invention is the provision of anchoring means for an actuator, as set forth, having means thereon for moving said actuator laterally out of the path of travel of ironer shoe-operating mechanism normally engageable with the actuator, whereby to render said mechanism inoperative.

2

Still another object of my invention is the provision of an actuator of the above type and novel mounting means therefor which is simple and inexpensive to produce and install, which is efficient in operation, and which is rugged in construction and durable in use.

Other objects and advantages of my invention will become apparent from the following detailed specification, appended claims, and attached drawings.

Referring to the drawings, which illustrate the invention, and in which like characters indicate like parts throughout the several views:

Fig. 1 is a view in plan of a multiple garment ironing machine, built in accordance with my invention;

Fig. 2 is a fragmentary view partly in elevation and partly in section, taken substantially on the line 2—2 of Fig. 1, and on an enlarged scale;

Fig. 3 is a fragmentary view partly in plan and partly in section, as seen from the line 3—3 of Fig. 2, some parts removed and some parts being broken away;

Fig. 4 is a fragmentary detail in section, taken substantially on the line 4—4 of Fig. 3; and

Fig. 5 is an enlarged fragmentary detail, taken substantially on the line 5—5 of Fig. 3.

Referring with greater detail to the drawings, the numeral 1 indicates in its entirety a supporting structure comprising a turntable 2 and a plurality of pedestal-like bases 3. The turntable 2 includes an annular supporting plate 4 secured to a concentric annular hub 5 by means of a plurality of radial arms 6. The plate 4 is reinforced by concentric annular flanges 7 and 8, the latter of which is made from structural angle iron welded to the plate 4 adjacent its peripheral edge. Depending flanges 9, one of which is shown, form bearing brackets journalling wheels 10 for rotation upon an endless circular track 11.

The bases 3 are in circumferentially spaced relation on the turntable 2 and are each equipped with one of a plurality of ironing devices 12 each having a relatively stationary pressing shoe 13 and a relatively movable pressing shoe 14. Each shoe 14 is provided with arms 15 rigidly secured thereto, projecting radially inwardly of the turntable and pivoted at their intermediate portions to their respective bases 3, as indicated at 16. The ironers 12 have identical operating mechanisms for moving their respective movable shoes 14 from the closed position shown in Fig. 2 to a spread-apart open position and vice-versa. For the sake of brevity, but one of the operating mechanisms or units will be described.

An adjustable link 17 is pivotally secured to the

radially inner end of the arm 15, as indicated at 18. The lower end of the link 17 is provided with a roller, not shown, but which is adapted to ride in a cam slot 19 in a vertical bracket 20 rigidly secured to the annular plate 4. Also pivotally secured to the lower end of the link 17 is the outer end of a piston rod or plunger 21 which is equipped with a piston, not shown, but contained within a fluid pressure-operated cylinder 22 hingedly secured, as indicated at 23, to the 10 pedestal 3. A second fluid pressure operated cylinder 24 is pivotally secured to the frame or pedestal 3, as indicated at 25, and is provided with a piston-equipped plunger rod 26 which has pivotal engagement with the arm 15 intermediate 15 its pivot 16 and its inner end, as indicated at 27. The movable shoe 14 is biased toward an ironer-open position in a direction away from engagement with the relatively fixed shoe 13 by a coil tension spring 28 anchored at its opposite ends 20 to the turntable 2 and the intermediate portion of the link 17.

Ironing machines of this character are generally constructed to provide a padded ironing shoe and a metallic faced heated ironing shoe. In this case, the stationary shoe 13 is padded and preferably provided with a cloth cover while the relatively movable shoe 14 is hollow and is heated by suitable means such as live steam. For introducing the heating medium to the hollow movable shoe 14, I provide an inlet pipe 29, the lower end of which is rotatably connected to the upper portion of a steam manifold 30 through a packing gland or the like 31. The upper or input portion 32 of the manifold 30 is divided from the lower or exhaust portion 33 thereof. A plurality of inlet tubes 34 lead one each from the input chamber 32 of the manifold to one of the movable shoes 14. The shoes 14 are each provided with drain pipes or tubes 35 that are connected to the lower exhaust portion 33 of the manifold 30. The inlet and drain tubes, being flexible in part, do not interfere with the freedom of movement of the movable shoes 14. Condensate from the shoes 14 passes through the tubes 35 into the exhaust chamber 33 from whence it is removed through a drain pipe 36 connected to the manifold 30 by a packing gland 37 and a fitting 38. The packing gland connections 31 and 37 permit rotation of the manifold 30 while the inlet pipe 29 and drain 36 remain in a stationary condition.

Fluid under pressure is supplied to the several ironers, for moving the relatively movable shoes 14, from a source of fluid supply, not shown, through a pipe 39 which extends upwardly through the fitting 38, the packing gland 37, and the exhaust chamber 33 by means of a suitable joint or slip connection 40. The pipe 39 extends radially outwardly of the manifold 30 and branches off to the several ironers on the turntable 2. A branch connection 41 extends from the pipe 39 to a control valve 42. From thence, conduit means 43 and 44 lead to respective cylinders 22 and 24. The structure above described is more fully disclosed in my copending application filed February 15, 1950, Serial No. 144,341, and entitled "Multiple Ironing Machine," now Patent No. 2,632,965, dated March 31, 1953.

Continuous and uninterrupted rotary movement at a relatively slow speed is imparted to the turntable 2 by a motor 45 which drives a shaft 46 through connections, not shown, but contained within a gear box 47. A sprocket wheel 48 is secured fast to the shaft 46 and positively drives a link chain 49 which extends about

and is carried within a channel 50 formed by the outer peripheral portion of the annular plate 4 and the flange 8. The chain 49 is maintained in frictional driving contact with the flange 8 by an idler pulley 51 journalled to one arm of a bell crank 52 that is pivoted to a stationary quadrant or the like 53. Pin and socket connections 54 of a conventional design are utilized to maintain the idler 51 in a position to tighten the link chain 49. This arrangement provides an inexpensive but satisfactory drive for the turntable which rotates in a clockwise direction, with respect to and as shown by arrows in Fig. 1, moving each of the ironers 12 slowly past an operator's station X, see Fig. 1.

The control valve 42 of each operating mechanism is provided with crank arms 55 and 56 that are connected by links 57 and 58 respectively to respective carriers 59 and 60 that are provided with pairs of cam follower rollers 61 and 62 respectively. Said pairs of cam follower rollers 61 and 62 and the connections therebetween and the control valve 42 are fully disclosed in my above-mentioned copending application Serial No. 144,341, and do not, in themselves, comprise the instant invention. Hence, for the sake of brevity, detailed showing and description thereof is omitted.

I provide an actuator in the nature of a relatively stationary cam 63 disposed radially outwardly of the circular track 11 in the path of travel of the cam follower rollers 61, and adjacent one side of the operator's station X, for manipulating the control valve 42 of the ironer shoe-operating mechanisms as each thereof approach the operator's station. The cam 63 is rigidly mounted on a base member 64 which, at its lower edge portion, has secured thereto a pair of radially inwardly projecting legs 65. An arcuate flange element 66 connects the inner ends of the legs 65 and is adapted to overlie the annular flange 11' of the track 11. A pair of circumferentially spaced angular lugs 67 are rigidly secured to the track 11 by nut-equipped bolts or the like 68. The lugs 67 overlie the arcuate flange 66 and have screw-threaded therein a pair of clamping members in the nature of threaded bolts or the like 69 the lower ends of which engage the flange 66 and press the same into clamping engagement with the track flange 11'. Loosening of the clamping bolts 69 will permit movement of the cam 63 in a direction circumferentially of the track 11 or longitudinally of the direction of traveling movement of the cam follower rollers 61. The circumferential spacing of the lugs 67 and the length of the arcuate anchoring flange 66 is such that the cam 63 may be adjusted to an appreciable variation in distance from the operator's station. When the clamping screws 69 are tightened, the frictional engagement caused thereby by the anchoring flange 66 and the track flange 11' is sufficient to retain the cam 63 in place against whatever circumferential thrust is imposed thereon by the cam follower rollers 61 as the several ironers successively approach the operator's station X. A second actuator in the nature of an elongated arcuate cam 70 is disposed adjacent the opposite side of the operator's station X from the cam 63, in radially outwardly spaced relation to the track 11 and in the path of travelling movement of the cam follower rollers 62. The cam 70 is provided intermediate its opposite ends with a pair of depending supports 71 which are inturned 75 at their lower ends to provide feet 72. The feet

72 are mounted and guided for sliding movements on a base plate 73 having a pair of guide elements 74 welded or otherwise secured thereto and overlying the inturned feet 72. A reinforcing cross bar 75 extends between the supports 74 and has its opposite ends welded or otherwise rigidly secured thereto in overlying relationship to the guide elements 74. The base plate 73 is formed to provide a pair of radially inwardly projecting legs 76 that are welded at their inner ends to an arcuate anchoring flange 77 which is adapted to rest upon the track flange 11. A pair of circumferentially spaced angular lugs 78 are bolted to the track 11 in overlying spaced relationship to the flange 77 and have screw-threaded therein clamping screws 79, the lower ends of which are adapted to have clamping engagement with the arcuate flange 77 to frictionally anchor the same together with the cam 70 against movement circumferentially of the track 11. A shifter bar 80 has its upturned inner end pivotally secured to the intermediate portion of the reinforcing bar 75, as indicated at 81, and projects radially outwardly therefrom in a manner to enable the operator of the machine to shift the actuator cam 70 laterally into and out of the path of travel of the cam follower rollers 62. By loosening the clamping screws 79, the cam 70 and parts associated therewith, including the base plate 73 and anchoring flange 77, are movable longitudinally of the path of travel of the cam follower rollers 62 toward and away from the operator's station X.

The operation of the above-described machine is similar to that of the machine disclosed in my copending application above identified. As the turntable 2 rotates about its axis, the several ironers 12 thereon are successively moved to their open position as a result of movement of the several pairs of cam followers 61 imparted thereto by the cam 63, from their inoperative to their operative positions and consequent operation of the control valve 42. As each ironer 12 passes the operator's station X, the operator places a garment to be ironed upon the relatively stationary ironing shoe 13. Assuming that the cam 70 is moved laterally to its operative position in the path of travel of the cam follower rollers 62, each ironer 12, as it leaves the operator's station X, is successively closed into pressing engagement with the material to be ironed by engagement of the cam 70 with the cam follower rollers 62 moving the same from their inoperative to their operative positions. Speed of continuous and uninterrupted rotation of the turntable 2 is such that one revolution thereof is sufficient to complete an ironing operation. Hence, as each ironer having a garment between the ironing shoes thereof approaches the operator's station X, said ironer will be caused to open to permit shifting of the garment thereon for ironing a different portion of the garment or for removal of the garment from the ironer and the placing of a different garment to be ironed thereupon, after which the ironer will be closed and the ironing cycle repeated. When it is desired to shut down the machine for a given period of time, the shifter bar 80 is manipulated to move the actuator cam 70 laterally out of the path of travel of the several cam follower rollers 62. This will cause the

70 in directions longitudinally of the direction of traveling movement of their respective cam followers assures opening and closing of the garment ironers in desired relationship to the operator's station. If, for instance, it is desired that the several ironers be open for unloading and reloading for a longer period of time than normal, the cams 63 and 70 are adjustably moved to positions a greater distance from each other 10 and the operator's station X and thereafter anchored by tightening of their respective clamping screws 69 and 79. Obviously, when a shorter ironer open time interval is desired, the actuator cams 63 and 70 are adjustably moved toward one 15 another circumferentially of the track 11. The above mounting arrangement for the cams 63 and 70 precludes the anchoring of the cams directly to the floor and eliminates any error in the placement thereof such as sometimes occurs when said cams are bolted or otherwise anchored to the floor or like base of support.

20 My invention has been thoroughly tested and found to be completely satisfactory for the accomplishment of the objectives set forth; and 25 while I have shown and described a preferred embodiment of my novel device, it will be understood that the same is capable of modification without departure from the spirit and scope of the invention, as defined in the claims.

30 What I claim is:

1. In an ironing machine, relatively movable 35 cooperating supporting elements, one being a track and the other a wheel structure engaging said track, an ironer mounted for movement with one of said elements and having operating mechanism disposed adjacent the other said element, an actuator also disposed and movably supported adjacent said other element for engagement with and actuation of said operating mechanism, and 40 relatively shiftable interengaging means on said other element and said actuator for selectively positioning and adjustably connecting said actuator to said other element whereby the time of operation of said ironer may be predetermined and set for actuation thereof upon said relative movement of said elements.

2. The structure according to claim 1, wherein 45 a plurality of operating mechanisms and a plurality of cam-like actuators therefor are disposed adjacent said other supporting element, and wherein the plurality of actuators are separately and independently adjustably supported from said other supporting element for predetermined actuation of said operating mechanisms, upon relative movement of said elements.

3. The structure according to claim 1 wherein 50 a plurality of operating mechanisms and a plurality of actuators therefor are disposed adjacent said other supporting element, and separate supporting arms having their inner ends clamped to said track for relative adjustment therealong are rigidly connected at their outer ends respectively to said actuators.

4. In an ironing machine having a supporting 55 track, a machine supporting structure mounted for traveling movement on said track, operating mechanism for said machine including an actuator engaging element depending from said machine supporting structure adjacent said track, an actuator disposed in the path of travel of said engaging element and adjacent said track, and relatively shiftable interengaging means on said track and actuator and connecting said actuator to said track for adjustment therealong, whereby

machine during travel of said supporting structure along said track.

5. The structure recited in claim 4, wherein the track is circular and the relatively shiftable interengaging means on the track and actuator comprises an arcuate track engaging flange and a releasable clamping member engaging therewith.

6. The structure recited in claim 4, wherein a plurality of operating mechanisms and a plu- 10

rality of actuators therefor are disposed adjacent said track, and wherein the actuators are separate cam elements having adjustable supporting connection with said track.

JOHN H. LEEF.
